SUPPOSITORY

Stefan Klinghoffer, Buenos Aires, Argentina

Application July 30, 1941, Serial No. 404,576

5 Claims. (Cl. 128—1.1)

This invention relates to suppositories to be introduced into the vagina, urethra or rectum, and more particularly to suppositories containing a predetermined amount of radioactive matter such as radon.

The therapeutical properties of radon are well known. It is also known that medicinal preparations containing a comparatively small amount of radon are completely harmless to the human body. Nevertheless, the application of radon containing medicinal preparations has met with many difficulties due to the fact that the radon disintegrates after a very short time, a few days or a week at the most, losing its radioactive properties. Hence, medicinal preparations, such as suppositories, cannot be stored for any length of time if they shall not lose their radioactivity.

In accordance with the invention this drawback is overcome by maintaining the radioactivity of the suppository at a predetermined constant value. To this end, greasy or pasty matter, such as oil of theobroma or coconut butter is first rendered radioactive, for instance by impregnating and mixing it with radon gas. The thus prepared greasy matter is shaped into the usual elongated cone shaped bodies. A member which generates radon atoms and which for the sake of simplicity is referred to in the following as a radioactive stabilizer is now introduced into the shaped greasy body. This radioactive stabilizer consists of a flat member which bears a radon producing material. The radioactive stabilizer may be provided with a hole which is filled with a radon containing or generating material. The latter is dosed in such a manner that the number of radon atoms which are generated per time-unit is equal to the number of atoms produced by decomposition or disintegration of the radon containing substance. Thus it is possible that the total amount of radon atoms which are present in the substance used for therapeutical purposes does not undergo a change for any length of time. The radioactivity will be constant and will neither have decreased nor increased to any appreciable extent.

The cone shaped greasy material is enclosed in a tight fitting casing which is provided with a cover. The radioactive stabilizer is inserted into the cone through a hole of this cover and can be easily removed therefrom. The greasy body with its cover closed casing and the inserted stabilizer are enclosed in an open tube-shaped container having preferably one closed end portion of reduced diameter. The reduced end portion of the tube serves to support the

cone containing casing. The tube may be provided with a screw thread and a correspondingly threaded closing plug. Alternatively the tube may be closed with a stopper.

5 In a preferred embodiment of the invention the plug or stopper bears against the radioactive stabilizer so that the suppository including the stabilizer is supported between the reduced end portion of the tube and its closing member. The suppository may also be enclosed in a glass tube having a reduced end portion. After introduction of the suppository the upper end of the glass tube may be closed with a stopper of glass wool and closed by melting it off.

10 15 It is, accordingly, an object of the invention to provide an improved suppository containing a predetermined amount of radioactive matter such as radon.

20 Another object of the invention is to provide a device which renders it possible to maintain the radioactivity of a suppository at a predetermined constant rate.

25 Still an object of the invention is to provide a suppository of the character referred to which is provided with a removable radioactive stabilizer and supported in a tube shaped container.

30 These and further objects of the invention will become more apparent when the description proceeds, taken in connection with the drawing, wherein—

Fig. 1 is a vertical cross-sectional view of a suppository in accordance with the invention and

35 Fig. 2 is a horizontal cross-sectional view according to line 2—2 of Fig. 1.

Referring to the drawing, my improved suppository comprises an elongated body 10 having a cone shaped end portion. Body 10 consists of a greasy matter as is well known to those skilled 40 in the art, such as e. g. oil of theobroma or coconut butter. Body 10 is enclosed in a tight fitting casing 11 having an open top and which may consist of a cellulose derivative. Casing 11 is provided with a closure cap 12. The latter is provided with an opening 14 which permits the insertion of the radioactive stabilizer 15. Radioactive stabilizer 15 is key-shaped and has a lower elongated portion 16 provided with a hole 17. The portion 16 of stabilizer 15 extends into body 10. Hole 17 is filled with a radon generating material. Casing 11 cover cap 12 and stabilizer 15 are enclosed in the tube-shaped container 18. The latter has a body portion 20 of reduced diameter which supports the conical end portion of casing 11. Tube 18 is tightly closed by stopper

21 which bears against the upper end of stabilizer 15. Hence, it will be seen that body 10 carrying casing 11 is supported by the reduced portion 20 of tube 18 and by stopper 21.

The greasy matter of body 10 is first mixed with radon gas. This may be done in the following manner. The air is evacuated from the container which is provided with a stirrer and a heating device. The evacuated container is now connected with a storage vessel containing radon gas; then the material from which the suppository is formed is introduced into the container which is still partly evacuated. The container is heated and the material contained therein stirred to effect a mixture of radon with the suppository material. The thus prepared mixture is shaped into the form of the body 10.

My suppository may be stored for any length of time and it will always retain its predetermined radioactivity due to the action of the 20 radioactive stabilizer 15.

When it is desired to use the suppository, stopper 21 is removed from container 18. Then 25 radioactive stabilizer 15 and closure member 12 are removed and body 10 discharged from casing 11 by slight pressure. The suppository is now ready for use.

Various changes and modifications may be made to the details of construction of the invention without departing from the broader spirit and scope thereof, as set forth in the following claims.

I claim:

1. A suppository comprising a radon carrying body of a pasty medicinal material, a casing for said body, a removable radioactive stabilizer having a head portion protruding from said body and a lower portion in said body for carrying a radon producing material, an open end container enclosing said casing and the head portion of said stabilizer, said container having a reduced end portion supporting said casing and a closure member for closing the open end of said container.

2. A suppository comprising a radon carrying conical body of a pasty material, a casing for said body, a removable flat radioactive stabilizer having a lower portion extending into said body and

5 a cavity in said lower portion for the reception of a radon producing substance, a tube-shaped open-end container enclosing said casing, said container having a reduced end portion supporting said casing and a closure member for closing the open end of said container.

3. A suppository comprising a radon carrying elongated conical body of a pasty material, a casing for said body, a cover for said casing, an aperture in said cover, a removable flat radioactive stabilizer having a lower portion extending through said cover aperture into said body and a cavity in said lower portion for the reception of a radon producing substance, a tube shaped open end container enclosing said casing, said container having a reduced end portion supporting said casing and a closure member for closing the open end of said container.

4. A suppository comprising a radon carrying elongated conical body of a pasty material, a casing for said body, a cover for said casing, an aperture in said cover, a tube shaped open end container enclosing said casing, a removable flat radioactive stabilizer having a lower portion carrying a radon producing substance extending through said cover aperture in said body and an enlarged head bearing against the inner wall of said container, said container having a reduced end portion supporting said casing and a closure member for closing the upper end of said container.

5. A suppository comprising a radon carrying elongated conical body of a pasty material, a casing for said body, a cover for said casing, an aperture in said cover, a tube-shaped open-end container enclosing said casing, a removable flat radioactive stabilizer having a lower portion carrying a radon producing substance extending through said aperture in said body and an enlarged wedge-shaped head, said container having a reduced end portion supporting said casing and a closure member for closing the upper end of said container, said stabilizer bearing with its wedge-shaped head against said closure member and with its side parts against the inner wall of said tube shaped container.

STEFAN KLINGHOFFER.
